(57) **CLAIM**

The ornamental design for inflator, substantially as shown and described.

DESCRIPTION

FIG. 1 is a front perspective view of inflator, showing my new design;

FIG. 2 is a perspective view of the inflator in a state of use;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Used for tires, balls, inflatable pads, kayaks, inflatable beds, inflatable toys, etc., including but not limited to the above inflatable work that requires inflatable products.

The broken lines in the drawings illustrate the portions of inflator, which form no part of the claimed design.
